UNITED STATES PATENT OFFICE.

CALEB K. LEEDY, OF MOUNT VERNON, OHIO.

DESIGN FOR A PUZZLE-BOARD.

SPECIFICATION forming part of Design No. 22,265, dated March 7, 1893.

Application filed November 14, 1892. Serial No. 452,005. Term of patent 7 years.

To all whom it may concern:

Be it known that I, CALEB K. LEEDY, a citizen of the United States, and a resident of Mount Vernon, in the county of Knox and

State of Ohio, have invented and produced a new and original Design for a Puzzle-Board, of which the following is a specification.

The leading feature of my design consists in a series of triangular figures located one within the other, and appearing in contrasting shades of color, as indicated by the conventional lining, or shading, on a board.

In order that my invention may be fully understood I will proceed to describe it with reference to the accompanying drawings, in which:—

Figure I is a plan view of a puzzle board showing my design. Fig. II is a vertical section thereof on the line II—II of Fig. I looking in the direction of the arrows. Fig. III is a vertical section of the same on the line III—III Fig. I looking in the direction of the arrows.

1 is a plain quadrangular surface surrounded by side walls 2, and gradually inclined 25 from the latter to a central plane 3.

4 is an inner triangular figure.

5 is an outer triangular figure and 6 is an intermediate triangular figure occupying the space between the inner and outer triangular 30 figures. These triangular figures may be of contrasting shades of color to more clearly define them. The triangular figures have circular depressions 7 arranged as shown.

Having thus described my invention, the 35 following is what I claim as new therein and desire to secure by Design Letters Patent:

The design for a puzzle board, substantially as herein described and shown.

CALEB K. LEEDY.
